UNITED STATES PATENT OFFICE.

JOHN B. HONOR, OF NEW ORLEANS, LOUISIANA.

ELEVATOR APPARATUS.

SPECIFICATION forming part of Letters Patent No. 767,888, dated August 16, 1904.

Application filed March 16, 1904. Serial No. 198,473. (No model.)

To all whom it may concern:

Be it known that I, JOHN B. HONOR, a citizen of the United States, and a resident of New Orleans, in the parish of Orleans and 5 State of Louisiana, have invented a new and Improved Elevator Apparatus, of which the following is a full, clear, and exact description.

My invention relates to apparatus for elevating and transferring various materials, it being more particularly applicable to the coaling of vessels and the delivery of crushed rock and earth.

It consists in the various features and combinations hereinafter described and more particularly claimed.

Reference is to be had to the accompanying drawings, forming a part of this specification, in which similar characters of reference indicate corresponding parts in all the figures.

Figure 1 is a vertical transverse section of one embodiment of my invention on the line 1 1 of Fig. 2, certain parts beyond the plane of section being broken away. Fig. 2 is a 25 top plan view of the barge upon which the apparatus is mounted, the upper portion of the frame and supported elements being removed. Fig. 3 is an end elevation of the scale mechanism and its associated receptacle. Fig. 4 is 30 a side elevation thereof including also the lower receptacle or hopper, and Fig. 5 is a horizontal sectional detail of said hopper.

10 designates a barge or floating structure, upon the deck of which are secured opposite 35 retaining-bases 11 11. From these bases rises a frame F, consisting of inclined standards 12, connected by horizontal frame members 13 and preferably braced by diagonal rods 14. Upon the top of the frame is mounted a cross- 40 arm 15, projecting at one side for a considerable distance therefrom and a comparatively short distance at the opposite side. Upon this cross-arm moves a traveler 16 of automatic hoisting mechanism, which may be of 45 any desired type, here shown as comprising a bucket 16^a, from which and from the traveler cables 17 lead over blocks 18 and grooved pulleys 18^a, carried by the cross-arm to blocks 19 and pulleys 19^a, secured near the deck. 50 From these the cables pass over winches 20

21 22. These serve, respectively, to close the bucket and raise it, to open the bucket and drop it, and to move it back and forth upon the cross-arm. They are here shown as of the steam type, being supplied by a boiler 23, 55 situated upon the deck. Mounted upon the frame between the cross-arm and deck is a horizontal platform 24, in which is a substantially central opening 25. Upon the platform at opposite sides of the opening are 60 tracks or rails 28, upon which run wheels 29, carried by a base 30 of scale mechanism, of which there are here shown the levers 31, standard 32, and beam 33. Upon the scale-levers is supported a receptacle, which is here 65 illustrated as a cubical box 34, having inner inclined side walls 35 and an inclined bottom 36. In one side of this receptacle at the bottom of the incline is an opening across which moves a gate 37, mounted in guides 38. 70 Journalized in suitable bearings beneath the scale-base is a rod or shaft 39, having at the end adjacent to the gate an arm 40, which is connected with the gate by a flexible member 41, passing over a grooved pulley 42. At the 75 opposite end of the shaft is an arm 43, at the outer end of which is shown a pad serving as a treadle. Secured to the receptacle opposite the gate is a deflector 37^a, which directs the discharge from the receptacle-opening downward through the platform-opening. From the platform at the edge adjacent to the gate is an extension 44, conveniently supported by brackets 45 and having the rails 28^a in alignment with the rails 28 to permit the car to be 80 rolled clear of the platform-opening. At the opposite side of the car where the treadle is situated is a platform extension 46, supported by brackets 47, this serving as a stand for the operator who attends to the scale mechanism 90 and the discharge of the contents of its receptacle.

Beneath the opening in the platform 24, conveniently mounted between the frame members 13, is a receptacle or hopper, here 95 shown as consisting of inclined side walls 48 and a horizontal bottom 49. In this bottom is an opening surrounded by a plate or flange 50, upon which rotates a similar plate 51. From this latter plate a chute 52 extends out- 100

wardly over the side of the barge, it being capable of revolution through a considerable arc by virtue of the relative movement between the plates. In this chute, here shown 5 as directly below the hopper-opening, are overlapping elbow-sections 53, which in their movement by one another enable the end of the chute to be raised or lowered. The outer end of the chute may be supported upon a 10 boom 54, which is pivoted upon a bracket 55 by cables 56, attached to the chute and passing over blocks 57, depending from the boom, from which they may lead and be secured to a cleat 58 near the deck. The boom may be 15 raised and lowered to vary the position of the chute by cables 59, extending over a block 60, secured to the frame and then downward therefrom to a retaining-cleat 61 near the deck. Within the hopper is shown crushing mechanism 20 conveniently consisting of a toothed roll 62, the shaft of which is journaled in bearings 63, carried upon the outer faces of the hopper-walls. The roll may be rotated through a pulley 64, over which passes a belt 25 65 from a pulley 66, the shaft of which is mounted in bearings 67 upon the deck. From a pulley 66^a, fixed to the shaft of the pulley 66, a belt 68 extends to the pulley of an engine 69, which may be supplied with steam 30 by a boiler 70. Large fragments of material are caught between the forward teeth of the crushing-roll and bottom of the hopper and reduced to the proper size before passing through the opening.

35 Along one of the frame-standards may extend a pipe 71, supplied with a valve 72, within reach of the platform 24, through which pipe water may be introduced into the hopper.

The barge will be supplied with suitable 40 stans and other necessary apparatus of this character, which need not be here described.

In use my improved elevating apparatus is moved adjacent to the vessel or other point at which it is desired to deliver material with 45 the cross-arm extending over the supply, the chute being moved either laterally or raised and lowered until it discharges at the proper point. The bucket is now filled and brought over the upper receptacle in a manner well 50 known in this class of devices and drops its contents, whereupon it is weighed by the attendant, who then presses the treadle and permits the contents to fall into the hopper beneath. Here the large lumps are reduced to 55 the proper size by the crushing-roll, and it all passes through the chute to the vessel or the like which is being loaded. If, instead, the apparatus is being used for such work as the building of levees, it is not then necessary 60 or desirable to weigh the earth which is handled. Therefore the scale mechanism and its receptacle are moved upon the tracks to a position upon the platform extension 44 and the bucket allowed to drop its contents directly through the platform-opening into the 65

hopper. To aid in the passage of earth along the chute, water from the pipe 71 may be mixed therewith.

It will be evident that in my improved apparatus the range of movement of the elements and the capability of change in their relation renders it applicable to various uses and adaptable to many positions and that it enables the transfer of material to be accomplished very expeditiously. 75

Having thus described my invention, I claim, as new and desire to secure by Letters Patent—

1. The combination with a frame, of a receptacle mounted therein, a cross-arm carried by the frame above the receptacle, hoisting mechanism movable upon the cross-arm, a boom pivoted to the frame, a chute revolvable below the receptacle, and cables movably supporting the chute on the boom. 80

2. The combination with hoisting mechanism, of a receptacle into which said hoisting mechanism may deliver, crushing mechanism situated in the lower portion of the receptacle and coacting with the bottom thereof, and a movable chute opening from the receptacle 90 below the crushing mechanism. 85

3. The combination with a frame, of a hopper supported in the frame, a toothed roll rotatable in the lower portion of the hopper and coacting with the bottom thereof, and a chute revolvable about the bottom of the 95 hopper. 90

4. The combination with a frame, of a hopper supported therein, a cross-arm carried by the frame above the hopper, hoisting mechanism movable upon the cross-arm, crushing mechanism situated in the lower portion of the hopper and coacting with the bottom thereof, a chute opening from the bottom of the hopper and movable about the same, and 100 a boom pivoted to the frame and serving to support the chute. 105

5. The combination with a receptacle, of a platform situated above the receptacle, weighing mechanism movable upon the platform, 110 an upper receptacle provided with an opening and carried by the weighing mechanism, a gate controlling the receptacle-opening, and a deflector carried by the upper receptacle and serving to direct the discharge from the 115 opening into the lower receptacle. 120

6. The combination with a receptacle, of a platform situated above the receptacle, weighing mechanism movable upon the platform, 120 an upper receptacle provided with an opening at one side thereof and carried by the weighing mechanism, a gate movable across the receptacle-opening, and actuating means for the gate extending to the opposite side of the receptacle. 125

7. The combination with weighing mechanism, of a receptacle carried thereby and provided with an opening, a gate movable across the opening, a shaft journaled below the receptacle and extending to the opposite side 130

from the opening, arms upon the ends of the shaft, and means for connecting one of the arms with the gate.

8. The combination with a frame, of a platform carried thereby, tracks upon the platform, scale mechanism movable upon the tracks, a receptacle mounted upon the scale mechanism, a receptacle situated below the platform, and crushing mechanism operating 10 in the lower receptacle.

9. The combination with a frame, of a platform carried thereby and having an opening, a receptacle movably mounted upon the platform above the opening, a receptacle situated 15 below the opening, and hoisting mechanism movable over the receptacles and opening.

10. The combination with a frame, of a platform carried thereby and having an opening, a receptacle movably mounted upon the platform above the opening, a receptacle situated 20 below the opening, and a chute revolvable about the lower receptacle.

11. The combination with a frame, of a platform carried thereby and having an opening, 25 a receptacle movably mounted upon the platform above the opening, a receptacle situated below the opening, and a toothed roll rotatable in this lower receptacle and coacting with the bottom thereof.

12. The combination with a floating structure, of power mechanism carried thereby, a frame mounted upon the floating structure, hoisting mechanism operating upon the frame and connected with the power mechanism, an intermediate platform provided with an opening, a receptacle mounted above the platform and movable to free the platform-opening, a hopper situated below the platform, and a chute movable below the hopper. 30

13. The combination with a floating structure, of power mechanism carried thereby, a frame mounted upon the floating structure, hoisting mechanism operating upon the frame and connected with the power mechanism, an intermediate platform provided with an opening, a receptacle mounted above the platform and movable to free the platform-opening, a hopper situated below the platform, crushing mechanism within the hopper connected with the power mechanism, and a chute movable 45 50 below the hopper.

In testimony whereof I have signed my name to this specification in the presence of two subscribing witnesses.

JOHN B. HONOR.
